LOADING MECHANISM FOR PNEUMATIC GUNS

William S. Wells, Palo Alto, Calif., assignor to
Daisy Manufacturing Company, Plymouth,
Mich., a corporation of Michigan

Application June 28, 1948, Serial No. 35,593

5 Claims. (Cl. 124—51)

1

This invention relates generally to pneumatically operated guns and refers more particularly to improvements in the loading mechanism for repeating types of pneumatic guns.

Pneumatically operated guns of the repeater type are usually provided with a barrel through which shot in the form of pellets are propelled at considerable velocity by air under substantial pressure and also provided with a magazine adapted to contain a multiplicity of pellets in end to end relationship. The delivery end of the magazine is usually connected to the breech end of the barrel by a recess having a depth slightly greater than the length of the pellet in order to accommodate one pellet at a time. The pellet deposited in the recess from the delivery end of the magazine is ordinarily transferred to the breech end of the barrel by a mechanism which may be operated in response to manipulation of the gun cocking mechanism.

Heretofore, considerable difficulty has been encountered in repeatedly transferring pellets from the delivery end of the magazine to the breech end of the barrel without occasionally jamming one of the pellets in either the recess or the delivery end of the magazine. Due to manufacturing inaccuracies of the pellets, the latter frequently vary in length and may either become cocked in the transfer recess or may not be completely released from the delivery end of the magazine depending upon whether the pellets are longer or shorter than normal.

With the above in view, it is one of the objects of the present invention to reduce to a minimum any tendency for a pellet to jam in the transfer recess regardless of variations in length of the pellets. In accordance with the present invention, provision is made for guiding movement of the pellets into the transfer recess and for retaining the pellets in position in the recess for engagement by the transfer mechanism.

A further object of this invention is to associate the pellet guiding means with the pin usually provided for advancing a pellet from the breech end of the barrel to a firing position in the barrel.

The foregoing as well as other objects will be made more apparent as this description proceeds, especially when considered in connection with the accompanying drawings, wherein:

Figure 1 is a fragmentary sectional view of the breech end of a pneumatically operated gun equipped with shot transferring mechanism embodying the features of this invention;

Figure 2 is a sectional view taken on the line 2—2 of Figure 1;

Figure 3 is a second view similar to Figure 2 showing the parts in a different position of adjustment;

Figure 4 is a sectional view taken on the line 4—4 of Figure 1;

Figure 5 is a sectional view similar to Figure 4 showing the parts in a different position;

Figure 6 is also a sectional view similar to Figure 4 showing the parts in still another position; and

Figures 7 and 8 are respectively cross-sectional views taken on the lines 7—7 and 8—8 of Figure 2.

The pneumatically operated gun selected herein for the purpose of illustration is of the repeater type and is adapted to shoot shot in the form of pellets of orthodox design. As shown in the drawings, the pellets P are provided with rounded heads H at the front ends thereof and are formed with outwardly flaring tubular skirt portions S at the rear ends.

Inasmuch as the present invention concerns itself primarily with the pellet loading mechanism only the breech end of the gun is shown in detail herein and the air pressure control means is merely illustrated generally. Briefly, the gun comprises a frame 10 having a barrel 11 of a size enabling pellets P to be successively propelled therethrough at considerable velocity by air under pressure and having a magazine 12 spaced laterally from the barrel 11 in a common plane with the latter. The magazine 12 is adapted to contain a multiplicity of pellets P in end to end relationship and the delivery end of the magazine communicates with the breech end of the barrel 11 by a recess formed in the frame 10. The width of the recess 13 is sufficiently greater than the length of a pellet P to freely receive the latter, as shown in Figure 5 of the drawings.

The rearwardmost pellet P in the delivery end of the magazine 12 is deposited within the recess 13 by tipping the muzzle end of the gun upwardly sufficiently to enable the pellet to drop into the recess by the action of gravity. The pellet thus deposited within the recess 13 is moved inwardly through the recess into the breech end of the barrel by transfer mechanism designated generally herein by the reference character 14. The transfer mechanism 14 comprises a plate or arm 15 pivotally supported on the front end of the gun frame 10 by a pin 16 and having a projection 17 at the swinging end extending over the top of the recess 13. The arm 15 is normally urged in a shot transferring direction by a spring 18 looped intermediate the ends thereof around the pivot pin 16. One arm of the spring 18 is

60

65

anchored on the gun frame by a lug 19 and the other arm of the spring is anchored on the plate 15 by a lug 20. Movement of the plate or arm 15 in a shot transferring direction by the spring 18 is limited by engagement of the projection 17 with a shoulder 21 formed on the portion 22 of the gun frame at the rear side of the recess 13. Extending downwardly from the projection 17 into the recess 13 is an angular lug 23 having a pellet engaging flange 24 and having an inwardly extending flange 25 at the rear edge thereof. As shown in Figure 6 of the drawings, the flange 25 is adapted to assume a position opposite the delivery end of the magazine 12 when the transfer arm 15 is in its innermost position shown in Figure 3 of the drawings. Thus, the flange 25 serves to retain the rearwardmost pellet P in the delivery end of the magazine 12 while a pellet is transferred through the recess 13 into the barrel 11.

When the transfer arm 15 is in its normal position shown in Figure 2 of the drawings, the lug 23 is located in the recess 13 laterally outwardly from the delivery end of the magazine 12. In this normal position of the lug 23, the latter does not interfere with movement of a pellet from the delivery end of the magazine into the recess and the flange 24 is positioned for engagement with the pellet deposited in the recess. Inasmuch as the lug is normally located laterally outwardly with respect to a pellet P deposited in the recess 13, it follows that movement of the arm 15 from the position shown in Figure 2 of the drawings to the position shown in Figure 3 advances the pellet in the recess 13 to the breech end of the barrel 11.

In accordance with this invention, the pellet introduced into the breech end of the barrel 11 is advanced to the firing position shown in Figure 4 of the drawings by a pin 26. The pin 26 is slidably supported in the breech end of the barrel 11 and the rear end of the pin is connected to a block 27. The block 27 is suitably supported on the gun frame 10 for sliding movement and is secured to a slide 28. The slide 28 is in the form of an inverted channel shaped grip and the opposite side walls thereof are respectively slidably supported on opposite sides of the gun frame at the breech end of the latter.

The slide 28 also operates to swing the arm 15 to its normal position against the action of the spring 18 and to hold the arm in this normal position until the slide is retracted to the position shown in Figure 3 of the drawings. For accomplishing this result, a cam 30 is secured to the slide 28 in a position to engage the side edge 31 of the arm 15 opposite the side edge from which the lug 23 projects. The side edge 31 on the arm 15 is arcuate and is adapted to be engaged by the cam 30 as the slide 28 is moved from its rearwardmost position shown in Figure 3 of the drawings to its forwardmost position shown in Figure 2 of the drawings.

One of the advantageous features of the present invention is to retain the rearwardmost pellet P in the delivery end of the magazine 12 when the transfer arm 15 is in its normal position shown in Figure 2 of the drawings and to, in effect, guide the pellet into the recess where it may be engaged by the lug 23 before any tendency exists for the pellet to cock in the recess 13 and jam the loading mechanism. For accomplishing the above results a lug 32 in the form of a plate or blade is secured to the rear end of the pin 26 and projects laterally from

the pin in the direction of the recess 13. The location of the plate 32 on the pin 26 is such that when the latter is in its advanced position in the barrel 11 (Figure 4 of the drawings), the front edge of the plate occupies a position in the recess 13 at the inner side of the transfer lug 23 and directly opposite the delivery end of the magazine 12. The front edge of the blade 32 is provided with a forwardly extending projection 34 which extends into the delivery end of the magazine 12 and projects into the skirt of the rearwardmost pellet in the magazine.

It follows from the foregoing that as the slide 28 is moved rearwardly to retract the pellet positioning pin 26 from the barrel 11, the plate 32 moves rearwardly away from the delivery end of the magazine. However, the projection 34 is retained in the skirt of the pellet P and serves to guide the same into the recess 13. It will be understood that the portion 22 of the gun frame is slotted to provide sufficient clearance for operation of the blade 32. It will also be noted that the cam 30 is of sufficient length to maintain the arm 15 in its normal position while the blade 32 is retracted sufficiently to guide a pellet into the recess. In practice, the length of the cam 30 is predetermined to initiate swinging movement of the arm 15 just as the projection 34 on the plate 32 is withdrawn from the skirt of the pellet so that the pellet is immediately engaged by the lug 23 and transferred to the barrel 11 before it has an opportunity to become cocked in the recess 13.

In the present instance, rearward movement of the slide 28 to the position indicated in Figure 3 of the drawings performs the additional function of cocking the gun. Briefly, the cocking mechanism comprises a hammer 35 supported on a rod 36 for sliding movement fore and aft of the gun frame. The hammer 35 has an enlarged head 37 at the rear end and is normally urged by a coil spring 38 in a forward direction against an anvil 39 secured to the rod 36. The coil spring 38 is supported on the rod 36 between the head 37 on the hammer and a block 40 at the breech end of the gun frame. The hammer is moved rearwardly to compress the spring 38 in response to rearward movement of the slide 28 by an abutment 41 secured to the bottom of the block 27 in a position to engage the enlarged end 37 of the hammer. The hammer is held in its rearwardmost position wherein the spring 38 is compressed by an arm 42 pivoted at one end to the gun frame and having the free end extending rearwardly for engagement with the front side of the head 37 on the hammer. The arm 42 is released from the hammer 35 by the usual trigger arrangement indicated generally by the numeral 43.

Immediately upon release of the hammer 35 from engagement with the arm 42, the coil spring throws the hammer forwardly along the rod 36 into engagement with the anvil 39. In the present instance, the anvil 39 is operatively connected to a valve 44 located within the storage chamber 45 for air under pressure and adapted to close the outlet passage 46 for this chamber. The outlet passage 46 is connected to the barrel 11 at a point rearwardly behind the firing position of the pellet P so that air under pressure discharged into the barrel acts on the rear end of the pellet P and forces the latter through the barrel with considerable velocity.

The foregoing construction is such that rearward movement of the slide 28 from its forwardmost positions shown in Figures 1 and 2 of the

drawings performs three functions as follows: (1) releases the pellet transfer arm 15 to permit operation of the latter by the spring 18; (2) retracts shot positioning pin 26 and shot retaining blade 32; and (3) cocks the gun mechanism. On the other hand, return movement of the slide 28 swings the arm 15 back to its normal position shown in Figure 2 of the drawings, moves the pin 26 forwardly in the barrel to advance the shot or pellet to a firing position forwardly beyond the air discharge passage, and moves the plate 32 in retaining relationship with the rearwardmost pellet P in the magazine 12.

What I claim as my invention is:

1. A pneumatic gun comprising a frame having a barrel, a magazine spaced laterally from the barrel and adapted to retain a plurality of skirted pellets in end to end relation with the skirt portions extending rearwardly, a recess connecting the delivery end of the magazine to the breech end of the barrel, a member supported for sliding movement in directions fore and aft of the barrel, an extension on said member responsive to movement of the member to its forwardmost position to project into the skirt end of the rearwardmost pellet in the magazine and responsive to initial movement of the member rearwardly and upward tilting of the barrel muzzle end to guide said pellet into the recess, means at the rear side of the recess for disengaging the pellet from the extension upon continued rearward movement of the member, and means operating in timed relation to disengagement of the extension from said pellet to transfer the latter into the breech end of the barrel.

2. A pneumatic gun comprising a frame having a barrel, a magazine spaced laterally from the barrel and adapted to retain a plurality of skirted pellets in end to end relation with the skirt portions extending rearwardly, a recess connecting the delivery end of the magazine to the breech end of the barrel, a member supported for sliding movement in directions fore and aft of the barrel, an extension on said member responsive to movement of the member to its forwardmost position to project into the skirt end of the rearwardmost pellet in the magazine and responsive to initial movement of the member rearwardly and upward tilting of the barrel muzzle end to guide said pellet into the recess, means at the rear side of the recess for disengaging the pellet from the extension upon continued rearward movement of the member, and means responsive to said continued movement of the member in a rearward direction to engage the pellet at approximately the same time the skirt of the pellet is disengaged from the extension and to transfer said pellet into the breech end of the barrel.

3. A pneumatic gun comprising a frame having a barrel, a magazine spaced laterally from the barrel and adapted to retain a plurality of skirted pellets in end to end relation with the skirt portions extending rearwardly, a recess connecting the delivery end of the magazine to the breech end of the barrel, a member supported for sliding movement longitudinally of the barrel at the breech end of the gun frame in a plane including the axis of the delivery end of the magazine, a slot in the portion of the gun frame forming the rear wall of the recess providing clearance for

the passage of said member and having a depth less than the diameter of the pellet, an extension on said member adapted to project into the skirt portion of the rearwardmost pellet within the delivery end of the magazine when the member is in its forwardmost position and responsive to initial rearward movement of the member and upward tilting of the barrel muzzle end to guide said pellet into the recess against the rear wall of the recess, and transfer means engageable with the pellet at about the same time the extension is withdrawn from the pellet skirt for moving the pellet along the recess to the breech end of the barrel.

4. A pneumatic gun comprising a frame having a barrel, a magazine spaced laterally from the barrel and adapted to retain a plurality of skirted pellets in end to end relation with the skirt portions extending rearwardly, a recess connecting the delivery end of the magazine to the breech end of the barrel, a shot positioning pin supported for sliding movement within the breech end of the barrel, a part extending laterally outwardly from one side of the pin and movable into the recess to a position in obstructing relationship to the delivery end of the magazine in response to movement of the pin to its forwardmost position within the gun barrel, an extension on said part at the front edge of the latter adapted to project into the skirt portion of the pellet at the delivery end of the magazine in the forwardmost position of the part and responsive to initial retracting movement of the pin and upward tilting of the barrel muzzle end to guide said pellet into the recess, and transfer means engageable with the pellet at about the same time the extension is retracted from the skirt of the pellet for moving the pellet into the breech end of the barrel in advance of said pin.

5. A pneumatic gun comprising a frame having a barrel, a magazine spaced laterally from the barrel and adapted to retain a plurality of skirted pellets in end to end relation with the skirt portions extending rearwardly, a recess connecting the delivery end of the magazine to the breech end of the barrel, a member supported for sliding movement in directions fore and aft of the barrel, an element connected to said member and having a portion thereof projecting into the skirt end of the rearmost pellet in the magazine when said member is in its forwardmost position, said element being movable rearwardly upon rearward movement of said member to guide the pellet into the recess, upon upward tilting of the barrel muzzle end of the gun, and means for transferring the pellet to the breech end of the barrel after the pellet has been guided into the recess.
